(57) **CLAIM**

The ornamental design for a combination skewered food rack and warming tray, as shown and described.

DESCRIPTION

FIG. 1 is a top perspective view of a combination skewered food rack and warming tray showing our new design; FIG. 2 is a left end elevational view thereof; FIG. 3 is a left side elevational view thereof; FIG. 4 is a right end elevational view thereof; FIG. 5 is a right side elevational view thereof; FIG. 6 is a top plan view thereof; and, FIG. 7 is a bottom plan view thereof.

The broken line showing of a skewer and a marshmallow on the skewer is for the purpose of illustrating uses of the skewered food rack and forms no part of the claimed design.

The combination skewered food rack and warming tray of our new design can, for example, be used to make smores on a barbecue grill, wherein the marshmallows are heated on the skewered food racks as shown by the broken line showing of a skewer and a marshmallow on the skewer in FIG. 1, and graham crackers with chocolate are heated on the warming tray between the skewered food racks.
